UNITED STATES PATENT OFFICE.

WILLIAM ALBERT BALDWIN, OF SMITH'S FALLS, CANADA.

SULKY-PLOW.

SPECIFICATION forming part of Letters Patent No. 782,187, dated February 7, 1905.

Application filed February 24, 1904. Serial No. 195,070.

To all whom it may concern:

Be it known that I, WILLIAM ALBERT BALDWIN, a subject of the King of Great Britain, residing at Smith's Falls, in the county of Lanark, Province of Ontario, Canada, have invented certain new and useful Improvements in Sulky-Plows; and I do hereby declare that the following is a full, clear, and exact description of the invention, such as will enable others skilled in the art to which it appertains to make and use the same.

My invention relates to plows of the type called "sulky" or "riding" plows, wherein the machine is carried entirely on wheels and 15 adjustments are provided for shifting the plowshare vertically and horizontally with respect to the wheels.

The object of my invention is to improve this type of plow by providing certain additional and novel adjustments which give it a greater flexibility and, furthermore, by improving the arrangement and collocation of the parts.

One of the main features of my improved 25 plow resides in an adjustable mounting in the rear end of the plow-beam, which is mounted to slide vertically with respect to the pedestal which supports the rear wheel, and a gear-segment engaging with a rack on said pedestal 30 is provided in connection with a hand-lever whereby the share is raised and lowered with respect to the rear wheel, this being used in conjunction with a vertical adjustment of the front end of the beam, so as to keep the plow-share at all times level and prevent its nose 35 from dipping into the ground. This feature is intended especially for giving the plow-share a large range of vertical adjustment, so as to enable it to be raised in some instances 40 entirely off the ground.

My invention comprises further improvements in the form and arrangement of the steering-rod by which the rear wheel is joined to the front axle in this type of plow.

45 My invention further comprises other features, which will be hereinafter more particularly referred to, and pointed out in the claims.

In the drawings accompanying this specification I have shown one embodiment of my 50 invention, wherein—

Figure 1 is a side elevation of a plow embodying my improvements. Fig. 2 is a plan view thereof; and Fig. 3 is a plan view, on an enlarged scale, of the rear end of the plow beam and pedestal.

The plow-beam is designated by the numeral 4 and carries the standard 5, to which is secured the share 6, carrying the moldboard 7, the landside being preferably omitted in this plow, as its place is supplied by the steering-wheel or rolling landside 8. The front end of the beam is carried by two wheels 9 and 10, which are journaled on stub-axles 11, secured to the ends of rock-arms 12 13, the former secured rigidly on the transverse rock-ing axle 14, and the arm 13 is loosely mounted thereon and adjustable about the axle by means of a hand-lever 15, having a finger-lever 16, the bolt 17 of which engages with the notched quadrant 18 on the hub 19, fixed to the axle 14. On the axle 14 is also slidably mounted a yoke 20, having ears 21, to which is secured, by means of a bolt 22, the clips 23 of the pole 24. On the axle 14, at about its center, is rigidly fixed a lever-arm 25, and at the base 26 of this arm is provided an eye 26, forming a point of connection for a link 27, pivotally connected at its other end to a hand-lever 28, which is mounted on a pivot-pin 29 transverse to the axle in an extension-lug 30, formed at 30 one side of the yoke 20, and provided with a notched quadrant 31, with which engages the bolt of the finger-lever 32, this arrangement enabling the yoke 20 to be slidably adjusted on the main axle 14.

At about the center of the yoke 20 is pivotally connected the forward end of the beam 4 by means of clips 33 and a king-bolt 34, passing through the yoke. The lower end of the king-bolt also forms a point of attachment for the draft mechanism, comprising a draw-bar 35, forked at its forward end and carrying any suitable draft appliance, such as a doubletree 36 and swingletrees 37, if a two-horse draft is desired. This arrangement is 95 novel in that it enables the draft to be applied directly to the end of the beam, and hence always in line with the resistance of the plow-share, instead of to the axle 14, as heretofore. There is also mounted upon the beam 4 of the 100

plow a disk colter 38, suspended in line with and in proximity to the cutting edge of the share, and, as shown, it is journaled in a metallic fork 39, whose upper end is provided 5 with a socket 40, in which is fixed the curved rod 41, whose upper end is vertical and is adjustably secured to the beam by a clip 42.

The rear end of the beam 4 does not, as heretofore, rest directly upon the rear wheel 8 of the plow; but it is connected therewith by a novel adjustment. This wheel is journaled at the lower end of a post 43, which is vertically swiveled in the pedestal-block 44 at its upper end. This pedestal-block, which 15 projects forwardly, has in its front edge a T-shaped groove 45, and the standard 5, which is bolted to the rear end of the plow at 46 by means of a horizontal extension thereon, has a vertical T-shaped head or flange 48, adapted 20 to slide in the groove 45. At one side of the groove 45 on the pedestal-block 44 is formed a rack 49, with which engages a gear-segment 50, cast on the pivoted end of the hand-lever 51, which is fulcrumed on a pin 52, forming 25 one of the bolts by which the standard is secured to the beam, as shown in Fig. 3. The outer end of the bolt 52 passes through a stationary block 53, bolted to the right side of the beam and which carries the notched quadrant 54, engaged by the bolt 55 on a finger-lever 56, carried by the hand-lever 51, and the latter has preferably a flange 57 overhanging the edge of the segment 54, which serves as a support against lateral movement. 30 The lever 51 is also connected to the rock-lever 25 by a link 58, secured to the shank of the hand-lever.

It will be seen that the lever 51 is so connected to the front and rear wheels as to raise 40 and lower the plow-beam 4 horizontally, because when the lever is, for instance, pushed forward the gear-segment 50 is lowered upon the pedestal-block 44, lowering the rear end of the plow, and simultaneously the axle 14 is rocked so as to oscillate the wheel-arms 12 and 13 rearwardly, thus lowering the front end of the beam, and the reverse when the lever 51 is drawn back.

Another important feature of my improved 50 plow resides in the adjustability of the steering-wheel connection, which in this plow comprises a rod 59, pivoted at its front end to the ear 60 on the yoke 20. The post 43 of the rear wheel has on its upper end, as usual, a lever-arm 61, extending to the opposite side of the beam 4 from the ear 60. In former plows of this type the bar 59 was connected directly to the end of this lever 61, passing diagonally across the beam. In my present 55 plow, however, it is extended parallel to the beam, and thus is out of the way of the seat-post and other parts fixed to the beam and at the same time has an adjustable connection with the lever 61 by means of a bar 62, pivoted on a pin 63 at the end of the lever

61 and bifurcated at its opposite end 64, which is bored to receive the end of the rod 59. The latter is threaded, as shown at 65, and has mounted thereon in the recess 66 of the bifurcated end 64 a nut 67, by adjusting which on the rod 59 its active length is varied. The front bifurcation of the end of the bar 62 is also provided with recurved lugs 68 69, which embrace the flange 70 on the hub of a locking-block 71, loosely mounted on the 70 rod 59, and thus held in operative relation with the bar 62. The free end of the block is formed to abut against the rear face of the upstanding portion 72 of the pedestal-block, in which the groove 45 is formed, this abutment taking place when the steering-wheel 8 is accurately in line with the beam, so that the wheel is absolutely prevented from being thrown out of line by the pressure of the land or sidewise effort of the share, as it might 85 otherwise do by reason of the bending of the rod 59. The locking-block 71 may also have a small snug 73 forged thereon, which forms a rest to support the block against the lug 69 when it is thrown over out of contact with the 90 pedestal-block, as when it is desired to turn the plow or shift it laterally, so as to prevent the block 71 from falling completely over.

The seat of the driver (designated 74) is preferably mounted on a post 75, secured to 95 the side of the pedestal-block 44, and the locking-block 71 is readily manipulated by the driver from his seat, as well as the various adjusting-levers 15, 28, and 51.

Scrapers 76 and 77 are shown as applied to 100 the colter 38 and rear wheel 8, respectively; but these form no part of the present invention.

While I have shown in the accompanying drawings the preferred form of my invention, 105 it will be understood that I do not limit myself to the precise form shown, for many of the details may be changed in form or position without affecting the operativeness or utility of my invention, and I therefore reserve the right to make all such modifications as are included within the scope of the following claims or of mechanical equivalents to the structures set forth.

Having thus described my invention, what 115 I claim as new, and desire to secure by Letters Patent, is—

1. In a riding-plow, the combination of a plow-beam, wheels at the front end thereof, a steering-wheel at the rear end thereof, means 120 for simultaneously raising and lowering both ends of said beam with respect to said wheels, a rod connecting the supports of the front and rear wheels and means embodying a locking device carried by such rod for preventing 125 throwing of the steering-wheel out of line by pressure of the share on the land.

2. In a riding-plow, the combination of a plow-beam, wheels on which the front end of 130 said beam is supported, vertical adjustments

for both ends of the beam, a steering-wheel supporting the rear end of the beam, a lever connected with said adjustments to operate them simultaneously whereby the plow-beam 5 is horizontally raised and lowered, and means embracing a rod 59 and a locking-block loosely mounted thereon for engagement with a relatively fixed part for preventing throwing of the steering-wheel out of line by pressure of 10 the share on the land.

3. In a riding-plow, the combination of a plow-beam, wheels on which the front end thereof is supported, vertical adjustments for both ends of the beam, a steering-wheel supporting the rear end of the beam, a lever connected with said adjustments to operate them simultaneously whereby the plow-beam is 15 horizontally raised and lowered, means embracing a rod 59 and a locking-block loosely mounted thereon for engagement with a relatively fixed part for preventing throwing of the steering-wheel out of line, and a pedestal-block supported from the steering-wheel and having upstanding portion to coöperate with 20 said locking-block.

4. In a riding-plow, the combination of a plow-beam, wheels on which the front end thereof is supported, vertical adjustments for both ends of the beam, a steering-wheel supporting the rear end of the beam, means for operating said adjustments simultaneously, and means embracing a rod 59 and a locking-block pivotally connected with said rod for preventing throwing of the steering-wheel by 35 pressure of the share on the land.

5. In a riding-plow, the combination of a plow-beam, wheels supporting the front end thereof, vertical adjustments for both ends of the beam, means for simultaneously actuating said adjustments, a steering-wheel supporting the rear end of the beam, means embodying a rod 59 and a pivotally-mounted locking-block loosely mounted on said rod for preventing throwing of the steering-wheel 40 out of line, and adjusting devices for said means.

6. In a riding-plow, the combination of a plow-beam having a T-shaped head at its rear end, a rear wheel, a pedestal-block mounted 50 thereon and having a vertical T-shaped groove in which said head slides, and means for adjusting the rear end of said beam in said groove.

7. In a riding-plow, the combination of a plow-beam having a T-shaped head at its rear end, a rear wheel, a vertical post, a pedestal-block mounted thereon and having a vertical T-shaped groove in which said head slides, said post being vertically swiveled in the rear end of the pedestal-block, a rack formed on 55 one side of said groove, a gear-segment pivoted on said beam and engaging with said rack, and means for adjusting the position of said gear-segment, means connecting the supports of the front and rear wheels, and a locking-block loosely mounted on said means 60

to engage a fixed part to prevent movement of the rear wheel in one direction.

8. In a riding-plow, the combination of a plow-beam having a T-shaped head at its rear end, a rear wheel, a vertical post, a pedestal-block mounted thereon and having a vertical T-shaped groove in which said head slides, said post being vertically swiveled in the rear end of the pedestal-block, a rack formed on one side of said groove, a gear-segment pivoted on said beam and engaging with said rack, and a hand-lever fixed to said gear-segment, means connecting the supports of the front and rear wheels, and a locking-block loosely mounted on said means to engage a fixed part to prevent movement of the rear wheel in 70 one direction.

9. In a riding-plow, the combination of a plow-beam having a T-shaped head at its rear end, a rear wheel, a vertical post, a pedestal-block mounted thereon and having a vertical T-shaped groove in which said head slides, said post being vertically swiveled in the rear end of the pedestal-block, a rack formed on one side of said groove, a gear-segment pivoted on said beam and engaging with said rack, wheels supporting the front end of said beam, means for raising and lowering the front end of said beam with respect to said wheels, and means operating simultaneously the front 85 and rear adjustments, means connecting the supports of the front and rear wheels, and a locking-block loosely mounted on said means to engage a fixed part to prevent movement of the rear wheel in one direction.

10. In a riding-plow, the combination of a plow-beam having a T-shaped head at its rear end, a rear wheel, a vertical post, a pedestal-block mounted thereon and having a vertical T-shaped groove in which said head slides, 95 said post being vertically swiveled in the rear end of the pedestal-block, a rack formed on one side of said groove, a gear-segment pivoted on said beam and engaging with said rack, a hand-lever fixed to said gear-segment, a main axle journaled on the front end of said beam, front wheels journaled on said axle, means connecting the supports of the front and rear wheels, and a locking-block loosely mounted on said means to engage a fixed part 105 to prevent movement of the rear wheel in one direction, a lever-arm fixed to said axle for rotating the same, and a connection between said arm and said hand-lever.

11. A riding-plow comprising a horizontal plow-beam having a rigid T-shaped head at its rear end, a standard carried thereby, a share mounted on said standard, a transverse axle at the forward end of said beam, front wheels journaled on said axle, a rear wheel, a pedestal-block supported thereby and in which said rear wheel is swiveled, a hand-lever fulcrumed on said beam, and means connecting said hand-lever with said axle and said pedestal-block to simultaneously raise and lower both ends of 115 120 125 130

said beam, and means connecting the supports of the front and rear wheels, and a locking-block loosely mounted on said means to engage a fixed part to prevent movement of the 5 rear wheel in one direction.

12. A riding-plow comprising a horizontal plow-beam having a rigid T-shaped head at its rear end, a standard carried thereby, a share mounted on said standard, a transverse axle 10 at the forward end of said beam, front wheels eccentrically journaled on said axle, a rear wheel, a pedestal-block supported thereby and in which said rear wheel is swiveled, a hand-lever fulcrumed on said beam, a lever- 15 arm fixed to said axle, a link connecting said lever-arm with said hand-lever, a rack formed on said pedestal-block, and a gear-segment formed on said hand-lever and meshing with said rack, and means, embodying a pivoted 20 locking-block, for preventing throwing of the rear steering-wheel out of line by pressure on the share, and a rod secured to a point at the forward end of the beam and at the opposite side from the steering-arm and extending 25 parallel with the beam and on which said locking-block is loosely mounted.

13. A riding-plow comprising a horizontal plow-beam having a rigid T-shaped head at its rear end, a standard carried thereby, a share 30 mounted on said standard, a transverse axle at the forward end of said beam, front wheels journaled on said axle, a rear wheel, a pedestal-block supported thereby and in which said rear wheel is swiveled, a hand-lever fulcrumed 35 on said beam, a lever-arm fixed to said axle, a link connecting said lever-arm with said hand-lever, a rack formed on said pedestal-block, a gear-segment formed on said hand-lever and meshing with said rack, a notched 40 quadrant fixed to the plow-beam, and a finger-lever on said hand-lever adapted to engage the notches of said quadrant, and means, embodying a locking-block, for preventing throwing 45 of the rear wheel out of line by pressure on the share, and a rod secured to a point at the forward end of the beam and at the opposite side from the steering-arm and extending parallel with the beam and on which said locking-block is loosely mounted.

14. In a riding-plow, the combination of a 50 longitudinal beam, a transverse main axle, a yoke slidably mounted on said axle, and a pole and draft mechanism connected directly with said yoke and having a draw-bar mounted directly on the pivot of the beam.

15. In a riding-plow, the combination of a 55 longitudinal beam, a transverse main axle, a yoke slidably mounted on said axle, a pole connected directly to said yoke, a king-pin pivots connecting said yoke to said beam, and a draw-bar pivotally mounted on said king-pin beneath the beam.

16. In a riding-plow, the combination of a 60 beam, a forward axle, a member 20 supporting the forward end of said beam and slidably

mounted on said axle, a steering-wheel supporting the rear end of said beam, a steering-arm 61 projecting laterally therefrom, a lateral member pivoted on said arm, and a connection between the end of said member and 70 a point on said member 20 at the opposite side of said beam, said connection extending parallel to said beam.

17. In a riding-plow, the combination of a 75 front axle, a beam connected thereto and laterally slidably thereon, a steering-wheel supporting the rear end of said beam, a laterally-extending steering-arm adapted to guide said wheel, a rod 59 secured to a point at the forward end of said beam at the opposite side 80 from said steering-arm and extending parallel to said beam, and a bar 62 extending transversely to said rod and connected to the rear end thereof and to the end of the steering-arm. 85

18. In a riding-plow, the combination of a 90 front axle, a beam connected thereto and laterally slidably thereon, a steering-wheel supporting the rear end of said beam, a laterally-extending steering-arm adapted to guide said 95 wheel, a rod 59 secured to a point at the forward end of said beam at the opposite side from said steering-arm and extending parallel to said beam, a bar 62 extending transversely to said rod and connected to the rear end thereof and to the end of the steering-arm, and a locking-block adapted to extend between said bar 62 and stationary part of the frame and prevent rotative movement of said steering-arm in one direction. 100

19. In a riding-plow, the combination of a 105 front axle, a beam connected thereto and laterally slidably thereon, a steering-wheel supporting the rear end of said beam, a laterally-extending steering-arm adapted to guide said wheel, a rod 59 secured to a point at the forward end of said beam at the opposite side from said steering-arm and extending parallel to said beam, a bar 62 extending transversely to said rod and connected to the rear end thereof and to the end of the steering-arm, and a locking-block pivotally connected with the bar 62 and adapted to be thrown into engagement with a part of the frame, whereby to prevent movement of said steering-arm in a forward direction. 110

20. In a riding-plow, the combination of a 115 beam, a front axle extending transversely thereto, a member 20 laterally slidable on said axle and supporting the front end of said beam, a rear wheel vertically swiveled with respect to said beam and having a laterally-extending steering-arm, and a connection between said steering-arm and the opposite side of said member 20, said connection comprising a bar 59 120 extending parallel to the beam and secured at its forward end to said member 20, and a transversely-extending bar connecting the rear end of said rod with the free end of said steering-arm. 125

130

21. In a riding-plow, the combination of a beam, a front axle extending transversely thereto, a member 20 laterally slidable on said axle and supporting the front end of said beam, a rear wheel vertically swiveled with respect to said beam and having a laterally-extending steering-arm, and a connection between said steering-arm and the opposite side of said member 20, said connection comprising a bar 59 extending parallel to the beam and secured at its forward end to said member 20, and a rectangularly-extending bar pivoted to the free end of said steering-arm and adjustably secured to the rear end of said rod. 5
22. In a riding-plow, the combination of a beam, a front axle extending transversely thereto, a member 20 laterally slidable on said axle and supporting the front end of said beam, a rear wheel vertically swiveled with respect to said beam and having a laterally-extending steering-arm, and a connection between said steering-arm and the opposite side of said member 20, said connection comprising a bar 59 extending parallel to the beam and secured at its forward end to said member 20, a transversely-extending bar connecting the rear end of said rod with the free end of said steering-arm, and a locking-block pivotally mounted on said rod and adapted to abut against part 30 of the frame. 15
23. In a riding-plow, the combination of a beam, a front axle extending transversely thereto, a member 20 laterally slidable on said axle and supporting the front end of said beam, a rear wheel vertically swiveled with respect to said beam and having a laterally-extending steering-arm, and a connection between said steering-arm and the opposite side of said member 20, said connection comprising a bar 59 extending parallel to the beam and secured at its forward end to said member 20, a transversely-extending bar connected at one end to said steering-arm and bifurcated at its other end, and slidably mounted on said rod, and a nut engaging with the rear end of said rod between the bifurcations of said bar. 35
24. In a riding-plow, the combination of a beam, a front axle extending transversely thereto, a member 20 laterally slidable on said axle and supporting the front end of said beam, a rear wheel vertically swiveled with respect to said beam and having a laterally-extending steering-arm, and a connection between said steering-arm and the opposite side of said member 20, said connection comprising a bar 59 extending parallel to the beam and secured at its forward end to said member 20, a transversely-extending bar connected at one 50
- end to said steering-arm and bifurcated at its other end, and slidably mounted on said rod, 60 a nut engaging with the rear end of said rod between the bifurcations of said bar, and a locking-block 71 loosely-mounted on said rod and operatively connected with said bar and adapted to be thrown over to strike the rear 65 face of an upstanding portion of the frame, whereby to prevent motion in a forward direction of said steering-arm. 70
25. A riding-plow comprising a horizontal beam, a transverse front axle, a yoke slidably mounted thereon, a king-pin 34 pivotally connecting said beam with said yoke, means for adjusting said yoke laterally on said axle, a steering-wheel vertically swiveled at the rear end of said beam, a laterally-extending steering-arm connected with said wheel, a rod 59 connected with one side of said yoke and extending parallel to said beam, a rectangularly-extending bar pivoted to the free end of said steering-arm and adjustably mounted on the 75 rear end of said rod, and a locking-block mounted on said rod and connected with said bar and adapted to be thrown into engagement with the rear face of a projecting portion of the frame, whereby to prevent forward motion 80 of said bar. 85
26. A riding-plow comprising a longitudinal beam, a transverse forward axle, supporting-wheels eccentrically journaled on said axle, a lever-arm fixed to said axle at an intermediate point thereof, a yoke slidably mounted on said axle, means for adjusting said yoke longitudinally of said axle, a vertically-swiveled connection between said beam and said yoke, draft means applied to said vertically-swiveled connection, a pedestal-block having a vertically-sliding engagement with the rear end of said beam, a rear wheel vertically swiveled on said pedestal-block, a laterally-projecting steering-arm connected with said wheel, a rod 90 59 extending parallel with said beam at one side thereof and connected at its forward end with said yoke, a transverse bar 20 adjustably connected with the rear end of said rod and pivoted to the free end of said steering-arm, 95 and a locking-block pivotally mounted on said rod and abutting against said arm and adapted to be thrown into engagement with the rear face of said pedestal-block. 100
27. In witness whereof I have hereunto set my 105 hand in the presence of two witnesses.

WILLIAM ALBERT BALDWIN. [L. S.]
